INDEX FOR GUIDE CARDS

William Hoge, Youngstown, Ohio, assignor to
The General Fireproofing Company, Youngs-
town, Ohio, a corporation of Ohio

Application November 24, 1933, Serial No. 699,624

7 Claims. (Cl. 129—16.8)

This invention relates to an improved index device for guide cards, and more particularly to a construction including a practical holder for receiving a novel removable and replaceable index member.

Accordingly, one of the objects of the invention is to provide a novel and durable holder construction that may be applied to the upper edge of a guide card or separator, thereby to receive and support an index member whose indicia bearing surface is disposed at an oblique angle to the body of the card, thereby making it possible to more readily view the index in examining the filing contents of the drawer.

15 A further object of the invention is to provide a substantial and rigid construction capable of withstanding the more or less frequent handling of the guide cards incident to locating the desired section of the filing material. That is to say, 20 it is proposed to provide a construction which lends itself to reinforcing the tab portion of the guide card which normally projects from the upper edge thereof so as to strengthen the card at this point and materially increase the life of 25 the card in service.

With the above and other objects in view which will more readily appear as the nature of the invention is better understood, the invention consists in the novel features of construction, combination and arrangement of parts, hereinafter 30 more fully described, illustrated in the accompanying drawing and defined in the appended claims.

A preferred and practical embodiment of the 35 invention is shown in the accompanying drawing, in which:—

Figure 1 is a perspective view of a portion of a guide card or separator having one form of the present improvements applied thereto.

40 Figure 2 is a front elevation of the construction shown in Figure 1.

Figure 3 is a side elevation of the structure shown in Figure 1.

45 Figures 4, 5 and 6 are perspective views of modifications of the holder shown in Figure 1.

Similar reference characters designate corresponding parts throughout the several figures of the drawing.

50 In its primary aspect, the invention includes in its organization the body member 1 provided at opposite edges thereof with the channels 2 and 3. As will be apparent from Figure 1 of the drawing, it is not essential that both of the channels 2 and 3 be formed integrally with the body

1, as illustrated, for example, in Figures 4, 5 and 6.

Referring further to the construction of Figures 1, 2 and 3, it will be observed that the holder consists of the main body portion 1 above referred to and carrying the channel 2, and a supplemental body portion 1a carrying the channel 3, the portions 1 and 1a being disposed respectively at the front and back of the tab portion T of the guide card C. For the purpose of fastening the body of the holder to the tab T, the members 1 and 1a may be connected by suitable eyelet rivets 4 which may be separate rivet fastenings or the metal of one member may be spun into a projecting flange or lip to fit in the corresponding opening of the other member, thereby to be pressed down after the fashion of a rivet or eyelet to securely attach the holder to the tab.

The arrangement above described provides a substantial and rigid type of holder in the respect 75 that the body of the holder, consisting of the two parts 1 and 1a, is rigidly clamped to the tab and the disposition of the parts serves to reinforce the tab. Furthermore, any strain imposed on the upper flange 3 by the lifting or manipulation of 80 the card will be transmitted to the rear body section 1a and will not entirely be focused on the fastening 4 from the same side of the card as might be the case where both flanges are integral 85 with the body.

A primary object in providing the opposite channels 2 and 3 is to receive and accommodate the offset edge flanges 5 and 6 of a transparent guard or sheath 7 which is bent at right angles along its medial portion to provide upper and 90 lower obliquely disposed wings. It will be apparent from the drawing that the said member 7 may be readily slid into position by placing the flanges 5 and 6 thereof within the channels 2 and 3. And, for the purpose of preventing the member 7 from accidentally sliding entirely through the channels, the body 1 may be provided with the offset yielding abutment 8 which 95 serves as a spring clip to hold the transparent sheath in the channel. The sheath or guard 7 100 is preferably made of celluloid or equivalent material and to insure that the same will not be collapsed under the pressure of handling the guide cards, by having its flanges sprung from disengagement with the said channels of the 105 holder, the same is preferably backed up by the label or a resilient indicia bearing member 9. This member is of substantially triangular or three sided formation with the edges of the wings or walls at the point 10 suitably connected so that 110

the member will exert more or less outward pressure on the transparent sheath 7 to firmly hold it in place. While the member 9 may have the index material printed on one face thereof so as 5 to be exposed through the upper oblique wall of the sheath 7, it will of course be understood that insofar as the invention is concerned the indicia may be on a separate strip that is simply clamped between one wall of the backing member 9 and 10 the inside face of the transparent sheath 7. In either case the triangular member serves to back up the sheath.

Figure 4 illustrates a simplified form of the invention wherein the body 1b is provided with the 15 flanges 2a and 3a formed directly from the body itself, the latter being attached to the front face of the tab T by the fastenings 4a. In this form, the body 1b may be provided with the abutment 8a. The holder thus described may receive the 20 transparent member 7 and backing member 9 previously referred to.

In Figure 5, there is shown a form of holder wherein the body 1c is provided with the flanges 2c and 3c formed integrally therewith, but the 25 body 1c, at the top edge of the tab, is offset rearwardly as indicated at 11, thereby to step the holder rearwardly to substantially align with the rear face of the tab. Also in this form of construction there may be used a reinforcement 30 member 12 which may be of steel, celluloid, cloth, or any other suitable material doubled or folded upon itself and placed astride the tab so that the wings thereof may be secured to the body of the card by the fastenings 13 or their equivalent. 35 The body 1c of the holder may be secured to the reinforcement and the tab by the fastenings 4c, and one end of the body may be provided with the abutment 8c to prevent the guard from passing entirely through the same.

40 Figure 6 of the drawing illustrates a holder having the body 1d also provided with the flanges 2d and 3d formed integral therewith, the said flanges adapted to receive a resilient metal sheath 14 having a window 15 for exposing the indicia member adapted to be inserted therebeneath.

The foregoing views serve to illustrate the range of modification that may be resorted to in providing a holder for supporting an indicia bearing member and its protective sheath at the correct angle to be readily observed by anyone in placing or removing filing material in the drawer. The arrangement described also facilitates the removal of labels as well as the celluloid window or sheath in the event that a different color label 50 or sheath is desired to replace the window or label. Not only does the offset sheath or guard protect the label during manipulation and filing, but at the same time the labels are protected from direct contact with the filing matter arranged 55 between the guides.

Without further description it is thought that the features and advantages of the invention will be readily apparent to those skilled in the art, and it will of course be understood that 60 changes in the form, proportion and minor details of construction may be resorted to, without departing from the spirit of the invention and scope of the appended claims.

I claim:

70 1. An index device for guide cards including

a holder having opposite channels, a resilient transparent guard member of angular cross-section provided with flanges at its edges for engaging in said channels, and a resilient backing member of substantially triangular cross-section 80 adapted to be inserted between the holder and the guard member.

2. An index device for guide cards including a holder comprising a body having keeper channels at opposite edges thereof, a transparent resilient guard member bent to provide upper and lower wings having flanges at their outer edges for engaging with said keeper channels, and a backing member folded into substantially triangular formation and adapted to be inserted between the transparent guard member and the holder. 85

3. An index device for guide cards including a holder comprising separate body members adapted respectively to engage opposite sides of the guide card, one of said members having a lower channel portion and the other of said members having a forwardly extending wall adapted to cover the top edge of the guide card and terminating in a channel lying opposite the first-mentioned channel, means for fastening said body members together and to the guide card body, a resilient guard member of angular cross-section provided with flanges for engaging in said channels, and a resilient backing member 95 insertable between the holder and the guard member. 100

4. An index device for guide cards including a holder having opposite channels, a resilient guard member of angular cross-section providing upper 110 and lower wings inclined obliquely toward the holder and having edge flanges for engaging in said channels, and a resilient backing member having angularly related wings adapted to be inserted between the wings of the guard member 115 and said holder.

5. An index device for guide cards comprising a holder including opposite channels both disposed at one face of the card, means for securing said holder to the guide card, a guard member of V-shaped cross-section provided with flanges at the edges thereof for engaging in said channels, whereby the apex of said guard projects away from the face of the guide card to which the holder is attached, and a backing member having 125 angularly related wings insertable between the body of the holder and the guard member.

6. An index device for guide cards including a holder having opposite keeper elements, a resilient transparent guard of angular cross-section 130 providing upper and lower wings inclined toward the holder and having edge portions interfitting with said keeper elements, and a member having angularly related wings insertable between the wings of the guard and the body of 135 the holder.

7. An index device for guide cards including a holder provided at its front side with a pair of upper and lower flange members constituting keeper elements and providing therebetween a 140 front opening, and a resilient guard of angular cross-section providing upper and lower wings inclined toward the holder and having edge portions interfitting with said keeper elements.
